ELECTRIC-DISCHARGE SYSTEM

Frederick E. Barstow, Needham, and Irving F. Eastman, Natick, Mass., assignors to Edgerton, Germeshausen & Grier, Inc., Boston, Mass., a corporation of Massachusetts

Filed Sept. 17, 1959, Ser. No. 840,591

7 Claims. (Cl. 315—241)

The present invention relates to electric-discharge systems and, though it is useful, also, in more general fields, it is particularly adapted for systems in which one or more flash condensers or capacitors are discharged through the gaseous medium of a gaseous-discharge device for such purposes as the production of a single flash of light or a repetition of flashes, as in flash photography, stroboscopic applications and the like.

For purposes of illustration, the light-flash-producing systems to which the present invention is applied are of the type disclosed in United States Letters Patent No. 2,722,629 and 2,756,365, issued, respectively, on November 1, 1955, and July 24, 1956, to Kenneth J. Germeshausen, embodying normally ineffective voltage-adding mechanisms, operative substantially simultaneously with the application of a triggering impulse to a flash device, to boost the value of the voltage available for discharging through the flash device. It will be evident, however, that the invention is also adaptable to other types of electric-discharge circuits, as well, such as those described in United States Letters Patent Nos. 2,478,901 through 2,478,907, issued August 16, 1949, to Harold E. Edgerton.

In summary, the present invention is directed to safety, hold-off, and voltage-level-regulating systems and circuits, particularly adapted for apparatus of the above-described character, wherein protection is afforded for variations in voltage of the flashing capacitor or capacitors or failures in the same, and control is provided over the capacitor charging rate and the tendency for the flashing device to hold-over its discharging following a flash.

An object of the present invention, accordingly, is to provide a new and improved electric system embodying such safety, hold-off and voltage-level-regulating circuits that automatically insure the proper performance characteristics of the system.

Other and further objects will be explained hereinafter and will be more particularly pointed out in connection with the appended claims.

The invention will now be described in connection with the accompanying drawings, Figs. 1 and 2 of which are schematic circuit diagrams of a preferred flashing apparatus, particularly emphasizing safety and hold-off features thereof, respectively.

In the drawings, positive and negative banks of parallel-connected flashing storage capacitors C_1 and C_7 are shown connected in a series discharge circuit between the anode 1 and cathode 2 of a three-electrode preferably gaseous-discharge flash-tube device 3. The voltage stored in the capacitor banks C_1 and C_7 is normally insufficient to produce breakdown and hence a discharge between the anode 1 and cathode 2 of the tube 3 in the absence of a triggering stimulus applied to the trigger electrode 4. The device 3 may, for example, be of the various types described in the said Letters Patent. A satisfactory device of this nature, is, for example, the type FX-29 xenon flash tube marketed by Edgerton, Germeshausen & Grier, Inc.

2

The capacitor banks C_1 and C_7 are charged from upper and lower conductor lines B_+ and B_- , connected, respectively, to terminals I and II. The initial source of energy for charging or storing voltage in the capacitor banks C_1 and C_7 is an alternating-current source, labelled "A.C.," such as a three-phase 120-208 volt, Y-connected, 380-800 cycle per second generator, having phase lines A, B and C and a ground line D. The phase lines of the source A, B and C, are, in turn, connected to respective pairs of power-leg windings A_1-A_2 , B_1-B_2 and $C_1'-C_2$ of a conventional magnetic amplifier switching circuit T_1 . Three control windings C_3 , C_4 and C_5 are provided, with the winding C_3 connected at its lower end to the ground terminal D and at its upper end, by conductor 5 to a terminal 5'. The control winding C_4 is connected by conductor 6 to the lower terminal of the capacitor bank C_7 , and by conductor 7, through a rectifier CR27 and a resistance R17, to the B_- conductor line. Control winding C_5 is connected by conductor 8 to a terminal 8' and by conductor 9 to a terminal 9'.

As an example, the power-leg windings A_1-A_2 , B_1-B_2 , $C_1'-C_2$ may have 330 turns each. Two control windings may each have 500 turns, a resistance of 180 ohms and a current requirement, for full control, of 7 milliamperes; whereas the third control winding, for a purpose later described, may be 1000 turns, and have resistance of 360 ohms, and a lesser full control-current requirement of 3.5 milliamperes. Connected to the right-hand ends of each pair of the power-leg windings A_1-A_2 , B_1-B_2 , $C_1'-C_2$, are oppositely-poled rectifiers CR3—CR4, CR5—CR6, and CR7—CR8, as is well known, to control the current path through the windings during each half cycle. See, for example, Transactions of the American Institute of Electrical Engineers; Part I, September 1952. Since the operation of such amplifiers is widely understood, it will not be explained herein in great detail other than to state that the rectifiers CR3—CR4, CR5—CR6 and CR7—CR8, such as Type 303C Westinghouse diodes, are respectively connected to Y-connected primary windings P1, P2, P3 of a power transformer T_2 . The cooperative step-up secondary windings S_1 , S_2 and S_3 of the power transformer T_2 , connect to terminals III, IV and V, with a common terminal connection VI. Diodes, such as Type 1N1127 Texas Instrument rectifiers, in series banks CR9 through CR14 connect the terminals III, IV and V to terminals I and II in order to provide full-wave rectification for the B_+ , B_- lines. As an example, a 420-volt alternating-current output from the transformer T_2 will produce, at terminals I and II a 900-volt direct-current voltage for charging capacitor banks C_1 and C_7 along the B_+ , B_- lines. The capacitor banks, indeed, may, for example, each comprise six parallel capacitors, as shown of total capacitance value of about 1750 microfarads.

Diodes CR3 to CR8 permit current to flow during the positive half of each cycle only through the upper windings A_1 , B_1 and C_1' . During the negative half of each cycle, the diodes pass current through the lower windings A_2 , B_2 , C_2 . In this mode of operation, the special cores in each winding are kept completely saturated, and there is no restriction to the rate of current flow. However, a small D.-C. current applied to one of the three control windings C_3 , C_4 and C_5 will control directly the flow of A.-C. current in the power windings by driving the cores out of saturation. Current in the power windings will be restricted as it tries to drive the cores back into saturation. By regulating power input to the step-up transformer T_2 , the control windings C_3 , C_4 and C_5 establish the rate at which charging current flows into the capacitor banks C_1 — C_7 . The degree of A.-C. control is directly proportional to the amount of D.-C. current which flows. At 7 ma., in the above example, there

is maximum restriction to current flow in the power windings A_1-A_2 , B_1-B_2 , C_1-C_2 . When current flows in the positive direction, say downward in the control winding C_3 , positive control is exerted. However, if current in one of the control windings reverses, it will oppose the controlling effect of the other windings, prevented by series diodes such as $CR2$ at terminal $5'$, and diode $CR27$, before mentioned.

As explained in the said Letters Patent, a gaseous-discharge switch VI is preferred, for triggering the flashtube 3 , the tube VI having an anode 9 , a control electrode 10 , a cathode 11 and a keep-alive electrode 12 , connected through a resistance $R11$ to the terminal VI . A plate transformer winding L_1 is connected between the anode 9 and terminal VI and the cathode 11 is returned through a resistance $R10$ to the $B-$ line. A capacitor $C14$, normally charged from terminals VI and II , through cathode resistance $R10$, will discharge through the primary winding L_1 and the tube VI , upon grounding of the control electrode 10 . This may take place by closing switch S , or any other initiating device or circuit, connecting the electrode 10 through capacitor $C15$ to the ground terminal D . The secondary winding L_2 then applies a negative pulse, say 15,000 volts for several microseconds, to the trigger electrode $4'$ of the flashtube 3 . This reduces the firing voltage to approximately the potential across the capacitor banks C_1 , C_7 . The discharge of capacitor $C14$, as explained in the said Germeshausen Letters Patent, causes the normally ineffective secondary winding L_3 , the upper terminal of which is connected to the flashtube cathode 2 , to reinforce, supplement or add to the negative potential already at the cathode 2 , further increasing the potential between the flashtube anode 1 and cathode 2 , and causing the flashtube 3 to fire. A light flash of, say, one millisecond duration, more or less, will thus emanate from the tube 3 . The network $R14-C16$ connected between the upper terminal of L_2 and the terminal VI acts as an isolation circuit at the grounded end of the high-voltage winding and is designed to prevent external arc-over from either electrode of the flashtube to the trigger winding. The before-mentioned cathode resistor $R10$ prevents the negative capacitor bank C_7 from discharging through the trigger tube VI .

A voltage regulating and level control circuit is also employed comprising the rectifier $CR1$, such as a Zener diode, connected to terminal $9'$ and thus to the control winding C_5 by conductor $9''$, and thence by conductor 8 to terminal $8'$ and the slider S' of a potentiometer $R5$ (connected in a bleeder network $R4-R5-R6$ between terminals VI and $B-$), back through resistor $R6$. The heavy-shaded components $CR1$, C_5 , R_4 , R_5 , R_6 and R_2 thus serve to provide for control of the winding C_5 , thus to adjust the voltage applied to the capacitor banks C_1 , C_7 by the slider S' . In addition, at some point of $B-$ voltage, the diode $CR1$ exercises controlling or regulating action, keeping the lower terminal of winding C_5 more negative than the upper terminal—such negative current flow in C_5 having a lessened effect upon the charging current control. If polarity reversal occurs, as the $B-$ voltage approaches a limit, current flows in the opposite direction in C_5 , regulating the bleeder current at $R5$. The action just described is essentially that of a bridge circuit. By varying the tap-off S' at $R5$, the point at which the bridge balances can be altered. Shifting the quiescent point changes the value of the $-B$ voltage. Conversely, if the line voltage changes, the resultant change in $-B$ voltage causes the magnetic amplifier T_1 to reinforce or oppose the A-C. current as necessary to return the $-B$ (and $+B$) voltages to normal.

As before stated, one of the important features of the invention resides in a hold-off or quenching circuit that prevents continuous arcing after the flash tube 3 has fired, caused by sufficiently high continued current in the discharge circuit. This circuit is shown in heavy lines in Fig. 2. With the capacitor banks C_1-C_7 fully charged,

the terminals of the control winding C_4 are both at the same potential. When, however, the flashtube 3 fires, the $B-$ capacitor bank C_7 discharges rapidly (in, say, one millisecond) and the upper terminal of C_4 returns to a near-zero potential. The long time constant of the network, consisting of $C13$, $R7$, and the control winding $C4$ combined with the isolating action of $CR27$, before-mentioned, result in holding the lower terminal of $C4$ at a negative potential. With a difference in potential across its terminals, current flows through the control winding $C4$ from the upper to the lower terminal 3 . As described earlier, positive D-C. current flow in the winding limits the rate at which A-C. current flows, thus effectively causing the magnetic amplifier T_2 to isolate and thus, in effect, to disconnect power source A , B , C . The reduced current, thus, will not sustain arcing in the flashtube.

As the capacitor $C13$ discharges through $R7$, the control-winding negative current will decrease, resulting in an increase charging current once more to the capacitor banks C_1 , C_7 —but at a time when there is no longer danger of flashing hold-over in the tube 3 , in view of the hold-off period, say of the order of tenths of a second, more or less, that permits the tube 3 to de-ionize.

The capacitor charging rate of the banks C_1 , C_7 is controlled by a current-limiting circuit. In the normal mode of operation with the Form-Run switch S'' in the Run position, shorting out resistor $R15$ in the $B-$ line, the voltage drop across $R16$, in series therewith, which is proportional to the charging current, places a positive potential on the upper terminal of control winding $C4$ in relation to the lower terminal. The potential difference produces a positive D-C. current in the control winding $C4$ (from the upper to the lower terminal) which is limited by before-described resistance $R17$. The control current causes the charging current to be limited to the desired charging rate.

If the Form-Run switch is moved to the Form position, the larger voltage drop creates a higher potential difference; considerably more current flows from the upper to the lower terminal of C_4 ; maximum restriction is placed on the charging current; and the voltage forms very slowly on the capacitors C_1-C_7 .

Because the before-described voltage-regulator circuit is only connected across the negative bank C_7 , a short-circuit or other malfunction in the negative circuit will produce an overvoltage on the positive bank C_1 . One of the circuits shown in heavy lines in Fig. 1 prevents this condition, as follows. Any decrease in voltage on the negative bank C_7 without a corresponding decrease in the positive bank C_1 will cause the upper terminal of the control winding C_4 to go positive in relation to its lower terminal. Positive current will flow through the control winding C_4 , thereby reducing the rate of voltage buildup on the capacitors to zero.

An unbalance in the $B+$ bank C_1 does not endanger the $B-$ bank C_7 because of the protection afforded by the previously described voltage regulator across the $B-$ bank, C_7 . Because a $B+$ unbalance might reverse the current in the control winding and aggravate the unbalance condition, the diode $CR2$ is inserted in circuit with the control winding C_3 to prevent the reversal of current.

If, for any reason, the voltage on both banks C_1 , C_7 becomes excessive, neon tubes $V3-V10$, indicated in heavy lines in Fig. 1, and connected between terminals I and $5'$, will flash over. The upper terminal of control winding C_3 then becomes positive. A positive D-C. current will thus flow through the control winding C_3 and the regulatory action will reduce the voltage. The circuit may, for example, be designed to operate at 950-1000 v.

Further modifications will occur to those skilled in the art and all such are considered to fall within the spirit and scope of the invention as defined in the appended claims.

What is claimed is:

1. An electric flash-producing system having, in combination, an electric flash device having a pair of principal electrodes and a trigger electrode, a source of energy, energy storage means, a charging circuit including switching means for storing voltage from the source in the energy-storage means, a discharge circuit for the energy-storage means connected to the principal electrodes and including normally ineffective means for supplying voltage, when effective, in the discharge circuit along with the voltage of the energy-storage means, means for supplying a trigger impulse to the trigger electrode and substantially simultaneously rendering the normally ineffective means effective, thereby to enable the energy-storage means to discharge through the discharge circuit in order to produce a flash of energy between the principal electrodes of the flash device, and means operable upon a component failure in the energy-storage means for controlling the switching means to disconnect the said source from the energy-storage means.

2. An electric flash-producing system having, in combination, an electric flash device having a pair of principal electrodes and a trigger electrode, a source of energy, energy storage means, a charging circuit including switching means for storing voltage from the source in the energy-storage means, a discharge circuit for the energy-storage means connected to the principal electrodes and including normally ineffective means for supplying voltage, when effective, in the discharge circuit along with the voltage of the energy-storage means, means for supplying a trigger impulse to the trigger electrode and substantially simultaneously rendering the normally ineffective means effective, thereby to enable the energy-storage means to discharge through the discharge circuit in order to produce a flash of energy between the principal electrodes of the flash device, and means responsive after the production of the flash of energy to current in the said discharge circuit of value sufficiently high to provide for continued current flow through the flash device for 40

controlling the switching means to disconnect the said source from the energy-storage means.

3. Apparatus as claimed in claim 2 and in which means cooperative with the said switching means is provided for regulating the voltage supplied from the said source to the energy storage means.

4. Apparatus as claimed in claim 2 and in which the last-named means comprises further energy-storage means, means operable upon the production of a discharge through the flash device for discharging the further energy-storage means, and means for controlling the switching means in response to the discharging of the further energy-storage means to effect the said disconnection.

15 5. Apparatus as claimed in claim 4 and in which the said switching means comprises a magnetic amplifier having control winding means and the said further energy-storage means is connected to discharge through the said control winding means.

20 6. An electric discharge-producing system having, in combination, an energy-discharge device, a source of energy, an energy-storing circuit connected between the source of energy and the energy-discharge device, magnetic amplifier means connected between the source and the energy-storing circuit, and means responsive to sufficiently high current discharged through the discharge device and connected to the magnetic amplifier means to control the same to isolate the said source from the energy-storage circuit.

25 7. Apparatus as claimed in claim 6 and in which the magnetic amplifier means is provided with control winding means and the isolating means comprises further energy-storage means connected with the magnetic amplifier control winding means in order to discharge there-through.
